UNITED STATES PATENT OFFICE.

JAMES F. MANN, OF PORTLAND, OREGON.

PORTABLE MERCHANDISE-DISPLAY CONTAINER.

Application filed May 29, 1928. Serial No. 281,510.

My invention relates to portable display bins or containers especially designed for containing candy, crackers and like goods, to be sold in bulk.

5 The object of my invention is to provide a display bin, or container, which will make a mass display of the goods being sold, thus to impress the customer that the goods are constantly kept fresh by the large amount sold 10 thereof, and that the goods sold to the customer are the same as those displayed in mass in the container. In that way the freshness of goods displayed serves to stimulate and suggest to the customer the desire to purchase, according to my experience. On the 15 other hand, where mass display is not maintained in the container, as where the container shows only a small quantity of the goods on hand, the customer may get the impression that he is being served from a left-over remnant of the goods.

A further object of my invention is to provide a display bin or container so arranged that the front end of the container will always hold a considerable mass of the goods.

A further object of my invention is to provide a display bin, or container, in which the mass display of the goods at the front end of the bin may be readily maintained by simply lifting the rear end of the container so as to tip it forward, and cause the goods to move forward by gravity into and fill the front end of the container. Furthermore, to provide a container adapted to be arranged in groups, 35 side by side, within a show-case.

A further object of my invention is to provide a container so arranged that besides fulfilling the objects above enumerated it will at the same time provide a space underneath the 40 container—that is between the bottom of the container and the bottom of the show-case or other supporting surface on which the container is set—adapted to serve as a store room for a reserve supply of the goods displayed 45 in the container; or for storing packages of definite quantities—for example one pound or two pound boxes of candy—so that when the customer wishes to purchase such definite quantity he may be supplied from the packages stored under the container.

I attain my said object in a portable merchandise display container comprising a body having a bottom and sides, one end of the container being arranged to provide a display 55 pocket of substantial depth below the bottom of the container, and adapted to hold a large

amount of the goods, and thus provide the mass display above referred to. Legs are provided at the opposite end of the container, said pocket portion of the container and said legs being arranged to support the bottom of the container a substantial distance above the surface on which the container is set, so as to provide room under the container in which to store a reserve supply of the goods. The 60 front end of the container is covered with a glass.

The above described and other incidental features of my invention and the details of construction, and utility, of my improved display bin, or container, are hereinafter fully described with reference to the accompanying drawings.

In the drawings:

Fig. 1 shows a perspective view of my display container illustrating the details of construction;

Fig. 2 shows a central longitudinal section of my display container, representing the same as filled with globular goods, for 80 example, candy, and illustrates the distribution thereof;

Fig. 3 shows in a fragmentary section of a modification in the front of my display container to adapt the same for being placed in 85 a show case or other housing having a vertical front; and

Fig. 4 shows in a view similar to Fig. 2 illustrating a further modification of my invention; namely, the top and rear end of the 90 container are closed by a cover having a hinged section.

Referring first to Figs. 1 and 2 inclusive, my invention consists of a body, preferably elongate, composed of a bottom *b* and sides, 95 *c, d*.

The front or display end of the body is arranged to provide a display pocket *e* of substantial depth below the bottom *b*. This pocket *e* is provided to hold a considerable 100 mass of the goods contained in the container, so as to effect mass display thereof as mentioned. The front of the container is covered by a glass *f* which is removable. The rear end of the container is provided with legs *g* corresponding in height with the depth of the walls of the pocket *e*, so as to support the bottom *b* of the container a substantial distance above the bottom of the show case, or other housing, or surface, on which my container is set.

As shown in Figs. 1 and 2 of the drawings

the top of my container is left open, also the rear end. The bottom of the rear end is inclined upward as at *h*, and thus the container may normally be kept filled with the goods as indicated by *i* in Fig. 2, with the goods at the front end of the container always making mass display as apparent from Fig. 2.

10 The upwardly inclined bottom section *h* facilitates taking some of the goods from the container from time to time in making sales. In other words, the rear end of the bottom of the container is somewhat raised and slopes downwardly inward to facilitate for example candy being taken from the container by a 15 scoop or the like.

By reason of the described construction of my container quite a portion of the goods stored in the rear end of the container may be removed without substantially affecting the 20 mass display of the goods at the front end of the container.

If preferred, or deemed more convenient with respect to the shelving, or show case, in which my container shall be placed the front 25 end thereof may be made vertical as shown in Fig. 3, but in other respects the construction is just the same as above described, therefore the parts are designated by similar letters, and the pocket of this modified construction 30 is designated *e* and the glass *f*.

The front of my container as illustrated by Figs. 1 and 2 is specially designed to be placed in show cases having sloping fronts whereas the modified construction illustrated 35 by Fig. 3 is adapted for show cases having vertical fronts.

In Fig. 4 I have shown a further modification of my invention, when to be used on a counter unprotected by a show case or other 40 housing. In order to meet this situation, I have provided a cover *j* preferably of glass, for the top of my container secured in grooves formed in the sides of the container. The cover *j* includes a section *i*, hinged as at *k*, 45 which may or may not be of glass. This sec-

tion has a downwardly extending portion *l* provided with a handle *m*, to facilitate the opening and closing of the container in having access to its contents.

In other respects the construction shown by Fig. 4 is similar to that shown by Figs. 1 and 2.

Furthermore in the construction illustrated by Fig. 4 a partition *n* is provided adapted to be inserted by means of grooves in the 55 sides of the container to hold the display portion of the container filled with the merchandise and permit the remainder of the goods to be taken out, without disturbing the display portion. 60

Other variations in details not affecting the principle of my invention may be made as deemed expedient by the manufacturer.

I claim:

1. A portable merchandised display-container 65 comprising, a body having a bottom and sides, one end of the container arranged to provide a display pocket of substantial depth below the bottom of the container and adapted to make a mass display of the goods, legs provided at the opposite end of the container and said pocket-portion of the container and said legs arranged to support the bottom of the container a substantial distance above the surface on which the container is set. 70

2. A portable merchandise display-container comprising, a body having a bottom and sides, one end of the container arranged to provide a display pocket of substantial depth below the bottom of the container and adapted to make a mass display of the goods, legs provided at the opposite end of the container, said pocket-portion of the container and said legs arranged to support the bottom of the container a substantial distance above the surface on which the container is set, a glass covering the front end of the body 85 and the opposite end of the bottom of the body being inclined upward. 75

JAMES F. MANN.
